FIGS. 1, 2 and 3 are, respectively, side elevational, front elevational and top plan views of one embodiment of my design for a trash can funnel;

FIG. 4 is a side elevational view of said embodiment shown in use on a trash can;

FIGS. 5 and 6 are fragmentary views with parts in section of said embodiment taken, respectively, on the lines 5—5 and 6—6 of FIG. 3;

FIGS. 7, 8 and 9 are, respectively, side elevational, front elevational and top plan views of another embodiment of my design for a trash can funnel;

FIG. 10 is a side elevational view of said other embodiment shown in use on a trash can; and

FIGS. 11 and 12 are fragmentary views with parts in section of said other embodiment taken, respectively, on the lines 11—11 and 12—12 of FIG. 9.

The trash cans illustrated in broken lines in FIGS. 4 and 10 are shown for illustrative purposes.

The subject application is a continuation-in-part of my prior co-pending design patent application S.N. D. 10,992, filed Mar. 15, 1968, and now abandoned.

I claim:

The ornamental design for a trash can funnel, as shown and described.
